UNITED STATES PATENT OFFICE.

PERRY S. MARTIN, OF HARRISONBURG, VIRGINIA, ASSIGNOR TO NEWTOWN GIANT INCUBATOR CORPORATION, OF HARRISONBURG, VIRGINIA, A CORPORATION OF VIRGINIA.

OIL-BURNING COLONY BROODER.

Application filed November 9, 1920. Serial No. 428,914.

To all whom it may concern:

Be it known that I, PERRY S. MARTIN, a citizen of the United States, residing at Harrisonburg, in the county of Rockingham 5 and State of Virginia, have invented certain new and useful Improvements in Oil-Burning Colony Brooders; and I do hereby declare the following to be a full, clear, and exact description of the same, reference being had to the accompanying drawings, forming part of this specification.

This invention relates to an oil burning colony brooder and has for its principal object the provision of such a brooder in 15 which the range of temperature between a point near the burner and a point directly under the hover edge shall be reduced from the usual forty degrees or more to twenty degrees and even less.

20 A further object lies in the provision of means for providing ample fresh air to the young chicks as well as sufficient air for combustion such means deflecting the warmed air for the chickens out of the sides 25 of the hover while carrying away the products of combustion through the upper central orifice in the deflector cone.

In the drawings,—

Figure 1 is an elevation of the brooder 30 showing certain of the parts in cross section;

Fig. 2 is a plan view with certain of the parts omitted and others broken away;

Fig. 3 is a central sectional view through the center of the burner; and

35 Fig. 4 is a horizontal section of the burner bowl taken on line 4—4 of Figure 3.

The brooder illustrated should be placed in a level position in the center of a well lighted and ventilated room about 12 by 14 40 or smaller, according to the size of the brooder used. The base 10 is open at the bottom but closed at the sides 11 and ends 12, so as to form a passage or chamber when placed upon the ground, the entrance to such 45 chamber being through the orifice 13 beneath the reservoir, and the exit being a similar orifice 14 directly beneath the center of the hover. The chimney 15 is a cylindrical tube serving the dual function of supporting the fuel reservoir and associated

parts and of supplying air to the chamber beneath the base 10, the casing being provided with holes 16 and 17 for this purpose and for the reception of the oil pipe 18 leading from the drip cup 19 to the burner bowl 55 20. The reservoir 21 rests upon the upper reinforced edge 22 of the oil fount so as to be protected by the casing 23 and has an outlet 24 extending into the oil fount 25 thereby maintaining the oil at the level of 60 the bottom of such outlet. The reservoir 21 is provided with the usual cork valve 27 connected to a rod 28 of greater length than the distance from the cork to the base 29 of the casing and fount, so that when the reservoir is placed on the fount the cork will be driven inward allowing oil to flow from the reservoir until it closes the mouth of the orifice 24, thereafter maintaining such level 65 constant in the well known manner. The 70 base 29 of the casing may be supported in any desired manner, as for example, by means of the tie rods 30 extending to a bar 31 extending transversely across the base 10 thereby firmly binding the base 29 against 75 the chimney 15.

A small flexible friction tube 35 extends through the oil fount 25 as at 36, making an oil tight junction, and extends upwardly in a helical line between the fount and casing 80 and ends after a complete revolution or more in a downturned spout 37 directly above the oil cup 19, the spout preferably being centrally located with respect to the mica window 38 closing a corresponding orifice in the casing 23. A small bracket 40 is secured to the side of the casing 23 and furnishes a pivotal support 41 for the drip regulating lever 42 as well as threaded supports for the adjusting screws 44 and 45 governing respectively the minimum and maximum flow 85 of oil through the flexible tube 35.

The supply of oil to the burner is controlled by a thermostat 48 of the usual form, preferably of the circular corrugated double 95 convex ether-alcohol type, secured to a bracket 49 clamped by the oil pipe 18 by means of the bolts or other fastenings 50. A thermostat lever 51 is hinged to the bracket as at 52 and is normally held against the 100

umbo 53 of the thermostat by means of the action of a weight 54 swung from the regulating lever 42 on the tube side of the pivot 41 and operating by adding its weight to that of the tube 35 to swing the lower end of lever 42 away from the thermostat bracket, but owing to the connection 55 between such lower end and the lever 51 serving to hold the latter in contact with the thermostat 10 umbo.

As the temperature increases the thermostat expands and pulls the lower end of the drip regulating lever 42 to the left against the action of the weight 54 and raises the 15 end of the tube 35 until the short arm of the lever comes into contact with the minimum adjusting screw 44 when further increase in temperature will be accommodated merely through the bending of the relatively long levers 42 and 51. The minimum 20 adjusting screw 44 is usually set to provide just sufficient flow of oil to operate the burner and the maximum adjusting screw is normally set so that the greatest quantity 25 of oil will be furnished that can be taken care of by the burner. These regulating screws are not made permanent for obvious reasons including the need for a very rapid flow on first using the brooder for example 30 and the necessity of entirely closing the flow when desired, which is accomplished by turning the minimum screw 44 so as to bring the spout 37 entirely above the surface of the oil in the fount 25.

35 The burner bowl 20 is secured to the oil pipe 18 and is supported at the proper elevation by means of a bracket 60 secured to the base 10 and so arranged that there should be a slight slope to the oil pipe from the 40 bend where it enters the chimney 15 down to the burner bowl in order to insure a proper flow of oil.

The burner bowl is a flat annular casting having a boss 62 threaded to receive the end 45 of the pipe 18 and a central orifice 63 bounded by the vertical flange 64 which forms one wall of the trough 65, the other wall being formed by the outwardly sloping external flange 66. The flange 66 has a slight groove 50 67 in its upper inner face to furnish a secure support for the outer perforated combustion tube 68. The inner flange 64 may likewise be grooved on its upper outer face to receive the inner perforated combustion 55 tube 70, but it is preferred that the latter should have a friction fit with the outer face of the inner flange and have the lower points of its vertical cleats 71 abutting the partitions 72 in the trough. This abutment 60 between the cleat and the partition will not interfere with the flow of oil over the partition, since the cleats 71 are slightly beveled at their lower ends to permit the spilling of oil between the cleat and the outer 65 annular face of the trough.

These partitions 72, which may be two in number as shown, or any number of pairs, serve an important function in the present invention, since they permit the burning of a large or small quantity of oil with equal 70 efficiency, and furnish a most satisfactory substitute for the tilting burner which has the serious disadvantage of smoking and giving off unburned fumes of hydrocarbons from the portion of the trough not supplied 75 with oil since the entire trough is invariably hot. With the simple form illustrated having but the two diametrically opposed partitions, the oil is delivered to the front end of the trough 65 in large or small quantity. If but a small quantity of oil is delivered the flame will be entirely confined to the front half of the burner, since the level of the oil in the trough will not be high enough to overflow the partitions 71. The 80 efficiency of the flame, however, will be just as high as if twice the quantity were delivered, since the level of the oil will be the same and the flame will be confined to the front half of the annular space between the 85 perforated combustion tubes 68 and 70 by virtue of the perforated cleats 71 which extend throughout practically the length of the inner tube 70. When full quantity of oil is used it naturally overflows the partition and both halves of the burner are used in the usual way, the flame then being annular and the entire annular chamber between the tubes being utilized. Thus it will 90 be seen that in the present device a stationary burner is utilized in combination with a stationary oil fount and reservoir, the appropriate flow being maintained by movement of the flexible friction tube 35 alone. 95

A circular baffle plate 75 is held against the downwardly extending legs 76 of the burner base by means of a tie rod 77 passing through the burner cap 78 and being secured thereto by means of a nut 79 which holds the cap in close engagement with the top of the inner tube 70 which receives the reduced central projection 80 of the cap. 100

The cowl 81 is of the usual conical shape, has a friction fit with the top of the outer combustion tube 68 and is provided at its 115 lower end with a circular series of air holes 83. The cowl preferably extends slightly into the circular opening 84 in the lower cone 85 of the radiator and has its flaring skirt somewhat larger than the burner bowl 20, but slightly smaller in diameter than the spreader 75.

A circular guard 87 preferably having its upper portion 88 of reticulated material, such as wire cloth, has a slot 89 to receive the oil pipe 18, and is held in place by means of a plurality of lugs 90, preferably three in number, secured to the base by appropriate fastening means. 125

It will be seen that the air for the chicks 130

and for the burner will be supplied through the holes 16 and 17 in the chimney 15 and will pass downwardly through the hole 13 through the passage in the base 10 and upwardly through the orifice 14. It will then be spread by the circular baffle 75, part of the air traveling upwardly against the guard 87 and part of it passing inwardly over the spreader and upwardly through the central hole 63 of the bowl and in the space between the cowl and the outer tube. Part of the air in this latter space will pass through the holes 83 and into the hover space while the remainder will pass through 15 the perforations in the tube and aid in supplying oxygen to the flame.

The products of combustion will all pass through the annular orifice between the cowl and the cap 78 and will pass through 20 the central opening 84 into the lower chamber of the radiator, this chamber having for its ceiling the disk 93 spaced from the angle of the radiator but supported therefrom by means of a plurality of small straps 25 94 between which the products of combustion pass into the upper chamber 95 of the radiator, and thence to the chimney 96 and out through the openings 97 in the upper part thereof, slightly above the top 30 of the hover 100. The top of the chimney 96 may be closed by a cap 101 held in engagement by any preferred means, such for example as the spring fingers 102. The radiator is supported from the hover by 35 straps 103 secured to the cone by means of the bolts 104, one of which serves to support the usual thermometer 105.

The hover 100 is provided with a pair 40 of brackets 107 which receive pivot pin 108 extending through the legs of a U-shaped bracket 109 secured to the base as at 110, this connection permitting the swinging of the hover into contact with the reservoir 21 in order to have convenient access to the 45 burner.

The hover 100 has depending legs (not shown) which rest on the floor of the brooder room when the hover is horizontal.

What I claim is:

50 1. In a brooder, a hover, a burner for heating said hover, a heat radiating member between said hover and burner receiving the products of combustion from said burner and discharging through said hover, a shield surrounding said burner, and a baffle beneath said burner for directing air against said shield and to the outside of said radiating member.

55 2. In a brooder, a hollow base having a plurality of openings and providing an air passage between said openings, a burner located above one of said openings, a hover, a member surrounding said burner for conveying the products of combustion therefrom and having a lower conical surface to

direct air heated by said burner toward the lower edges of said hover, and means for directing heated air toward said lower conical surface.

3. In a brooder, a conical hover, an annular burner centrally located within said hover, a circular shield surrounding said burner and spaced therefrom; a circular horizontal baffle beneath said burner and within said shield and means for directing 70 the air deflected by said baffle upwardly and outwardly equally in all directions toward the periphery of said hover.

4. In a brooder, a conical hover pivoted near its periphery having an opening at the apex, a similar but smaller cone also having an opening in its apex arranged coaxially with the hover and spaced therefrom, means forming a passageway from the inner cone through the opening of the hover 80 and discharging to atmosphere, a third cone secured to the smaller cone coaxial but opposed and forming with said second cone a lenticular heat radiating member, said third cone having an apical opening there- 85 in, a baffle between the second and third cones for preventing direct passage of air from one opening to the other whereby when a heating means is placed below the opening in the third or lower cone the products 90 of combustion will pass up through the lower cone to the baffle, around the baffle, upward through the second cone and will be discharged from there through said passageway, said products of combustion as 95 they pass through the second or intermediate cone heating the air between said intermediate cone and the conical hover.

5. In a hover, the combination of three concentric cones, each having an apical 105 opening, a burner concentric with the three cones and discharging its products of combustion into the lower cone, and means located between the lower and intermediate cones for preventing direct passage of the 110 products of combustion from said burner from the lower to the intermediate cone, and means for spacing the intermediate cone from the upper cone so as to provide an annular air chamber to be heated by the products of combustion from the burner, and means for directing air against the lower cone annularly about said burner said lower cone directing such air toward said heated chamber.

6. In a hover, a cone having its apex downward and having a central opening therein, an annular burner beneath said cone, a cylindrical shield surrounding said burner, a base having an opening beneath said burner and a circular baffle spaced from said burner, said base and said shield and coaxial with said cone, said burner, said shield and the opening in the base.

7. In a hover, a hollow base, having an 130

exit opening and an entrance opening, a conical hover pivoted to said base and lying entirely to one side of the entrance opening and extending beyond the base at the side away from the pivot, a burner located above the exit opening, a shield surrounding said burner, a baffle spaced from

the burner and shield and located immediately above said entrance opening, and means for deflecting the air passing between the burner and the shield in an upward and outward direction toward the periphery of said pivotal hover.

PERRY S. MARTIN.
